UNITED STATES PATENT OFFICE.

CHARLES B. MATTSON, OF PUYALLUP, WASHINGTON, ASSIGNOR OF ONE-HALF TO
EMMA P. CHADWICK, OF OLYMPIA, WASHINGTON.

OPERATING STRUCTURE FOR CLOSURES.

1,241,538.

Specification of Letters Patent.

Patented Oct. 2, 1917.

Application filed April 13, 1917. Serial No. 161,360.

To all whom it may concern:

Be it known that I, CHARLES B. MATTSON, a citizen of the United States, residing at Puyallup, in the county of Pierce and State 5 of Washington, have invented certain new and useful Improvements in Operating Structures for Closures; and I do hereby declare the following to be a full, clear, and exact description of the invention, such as 10 will enable others skilled in the art to which it appertains to make and use the same.

This invention relates to a mechanism particularly designed for closing gates, doors or the like, which mechanism is operated through the pivotal movements of trip or operating levers so that in case it is employed in connection with gates, the gates 15 may be opened by the striking and locking of a lever by a vehicle so as to eliminate the necessity of the person alighting from the vehicle for opening the gates. Or, the device may be applied for opening doors so that the doors may be opened by the foot of the operator pressing upon the pivoted 20 levers, and closed in the same manner.

With the foregoing and other objects in view, this invention consists in such novel features of construction, combination and arrangement of parts as will be hereinafter 25 more fully described, illustrated in the accompanying drawings and claimed.

In describing the invention in detail, reference will be had to the accompanying drawings wherein like characters designate 30 like and corresponding parts throughout the several views, and in which:—

Figure 1 is a view illustrating in side elevation the closure operating mechanism and showing the gates or closures open in dotted 35 lines;

Fig. 2 is a view looking at the opposite side of the mechanism from that shown in Fig. 1;

Fig. 3 is an end view of the mechanism;

Fig. 4 is a section through the mechanism, taken on the line 4—4 of Fig. 1.

Referring more particularly to the drawings, 1 designates the platform which supports the closures when in a closing position. The platform 1 is positioned over a pit and is supported by suitable standards 2. If it is so desired, the entire mechanism 50

may be inclosed within a housing indicated at 3.

The closures, which may be gates or doors, 55 which are indicated by the numerals 4 and 5 have depending arms 6 formed upon their lower outer corners which arms project downwardly through the platform 1 and are pivotally connected as shown at 7 to the outermost supporting standards 2 so as to 60 allow the closures 4 and 5 to swing in a vertical plane upon the pivot 7 for moving them into an open or closed position. A pair of guiding cleats 8 are carried by the 65 platform 1 and they are positioned for holding the lower free edges of the gates or closures 4 and 5, against accidental horizontal movement.

A shaft 10 is rockably supported by the 70 center standards 2 and it has a drum 11 mounted thereon which drum is preferably provided with a concaved periphery. The shaft 10 is rectangular shaped in cross section so that it will rotate in unison with the 75 rotation of the drum 11. A cable 12 is attached to the drum 11 for winding thereon and it passes over a sheave pulley 13 which is suspended from the under surface of the platform 1, downwardly from the sheave pulley 80 13 to and about a sheave 14 which extends upwardly from the base 15. The rope or cable 12 passes from the sheave pulley 14 to beneath an idler pulley 16 which is also supported by the base 15 and it is connected as 85 shown at 17 to the lower end of a trip lever 18. The trip lever 18 is pivotally supported intermediate its ends as shown at 19 and its upper end 20 projects above the casing 3. The upper end 20 is positioned in the path of 90 a vehicle or an operator's foot, so that when the lever is moved in the direction indicated by the arrow A in Fig. 3 of the drawings, the cable 12 will be pulled outwardly in the direction indicated by the arrow B 95 in Fig. 3 of the drawings. The outward pulling of the cable 12 will rotate the drum 11 and consequently the shaft 10 for swinging the closure members 4 and 5 upon their pivot 7, into an open position as indicated 100 in dotted lines in Fig. 1 of the drawings. The closures 4 and 5 are swung into an open position upon pivotal movement of the lever 18 by cables 21 and 22. The cable 21 has

one end connected to an eye 23 which eye is in turn carried by the upper end of a rod 24 which extends diametrically through the shaft 10 at an obtuse angle to the vertical as 5 clearly shown in Fig. 2 of the drawings, and it passes over a sheave pulley 25, and is connected as shown at 26 to an eye 27 carried by the lower end of the arm 6 which projects downwardly from the lower outer 10 corner of the closure member 4. The cable 22 is connected to an eye 28 carried by the lower end of the rod 24 and it passes about pulleys 29 and is connected to an eye 30 carried by the lower end of the arm 6 which 15 is formed upon the closure member 5. The eye 27 has a second cable 31 connected thereto, which passes over a sheave pulley 32 and is connected to the eye 28. A cable 33 is connected to the eye 23, passes over a pulley 34 and is connected to the eye 30.

The drum 11 has a second cable 36 connected thereto which passes about a pulley 37 and a second pulley 38. The cable 36 is connected to a lever 39 intermediate its ends 20 as shown at 40. The lever 39 has its lower end pivotally connected as shown at 41 to a suitable brace 42 and its upper end 43 projects above the top of the casing 3 and the platform 1 as clearly shown in Fig. 4 of the 25 drawings, so that when the lever 39 is moved outwardly into the position indicated in Fig. 4 of the drawings, the closure members 4 and 5 will be swung into a closed position, at which time the lever 18 will be moved 30 into an operative position, through the arrangement and connections of the various 35 ropes or cables.

When a vehicle strikes the upper end of the lever 20, it pulls the cable 12 in the 40 direction indicated by the arrow B in Fig. 3 of the drawings and this rotates the drum 11 for winding a limited amount of the cable 36 thereon. The rotation of the drum 11 as above mentioned will rotate the shaft 10 and consequently move the rod 24 so that 45 it will pull upon the cables 21 and 33 for rocking the closures 4 and 5 upon their pivots 7 and moving them into open position. The closures remain in an open position until the lever 39 is moved into the position 50 illustrated in Fig. 4 of the drawings, which unwinds the cable 36 from the drum 11, winds the cable 12 thereon and rotates the shaft 10 in a direction oppositely to which 55 it is rotated by the pivotal movement of the lever 18, causing the rod 24 to move in a direction for pulling upon the cables 22 and 31 which moves the closures 4 and 5 into their normal closed positions.

60 From the foregoing description taken in connection with the accompanying drawings the advantages of construction and of the method of operation of the improved operating structure for closures will be readily 65 apparent to those skilled in the art to which

this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

75 What is claimed is:—

1. In a device as set forth, the combination with a pair of pivotally mounted closure members, of cables connected to said members, a rotatably mounted shaft, a rod 80 extending diametrically through said shaft, said cables connected to the ends of said rod for pivotally moving said closure members upon rotation of said shaft, a drum mounted upon said shaft, a pair of cables 85 connected to said drum and wound about the drum in opposite directions, whereby when one of said cables is unwound from the drum said shaft will be rotated in one direction and when the other cable is unwound from the drum, the shaft will be rotated in an opposite direction, whereby said closure members may be moved in and out of closing position.

2. In a device as set forth, the combination with a pair of pivotally mounted closure members, of cables connected to said members, a rotatably mounted shaft, a rod 90 extending diametrically through said shaft, said cables connected to the ends of said rod 100 for pivotally moving said closure members upon rotation of said shaft, a drum mounted upon said shaft, a pair of cables connected to said drum and wound about the drum in opposite directions, whereby when one of said 105 cables is unwound from the drum, said shaft will be rotated in one direction and when the other cable is unwound from the drum the shaft will be rotated in the opposite direction, whereby said closure members may 110 be moved in and out of closing position, a pair of pivotally mounted trip levers, said last named cables being connected to said trip levers for rotating said drum and shaft upon pivotal movement of the trip levers.

115 3. In a device as set forth, a pair of pivotally mounted closure members, depending arms formed upon said closure members and extending downwardly from their pivoted corners, cables connected to said 120 arms, a rotatably mounted rectangular shaft, a rod extending diametrically through said shaft, said cables connected to the ends of said rod for moving said closure members into an open or closed position upon 125 rotary movement of said shaft.

4. In a device as set forth, a pair of pivotally mounted closure members, depending arms formed upon said closure members and extending downwardly from their pivoted 130

corners, cables connected to said arms, a rotatably mounted rectangular shaft, a rod extending diametrically through said shaft, said cables connected to the ends of said rod for moving said closure members into an open or closed position upon rotary movement of said shaft, a drum mounted upon said shaft, cables connected to said drum, a pair of pivotally mounted trip levers, said

last named cables being connected to said trip levers for rotating said drum and shaft upon pivotal movement of said trip levers.

In testimony whereof I affix my signature in presence of two witnesses.

CHARLES B. MATTSON.
